DESIGN FOR A PHONOGRAPH TONE ARM OR THE LIKE

Joseph B. Federico, New Baltimore, Mich., as-
signor to The Astatic Corporation, Conneaut,
Ohio, a corporation of Ohio

Application January 6, 1947, Serial No. 135,963

Term of patent 7 years

(Cl. D26—14)

To all whom it may concern:

Be it known that I, Joseph B. Federico, a citizen of the United States, residing at New Baltimore, in the county of Macomb and State of Michigan, have invented a new, original, and ornamental Design for a Phonograph Tone Arm or the like, of which the following is a specification, reference being had to the accompanying drawing, forming part thereof.

Figure 1 is a perspective view of the phonograph tone arm or the like embodying my novel design.

Figure 2 is a front elevation of the phonograph tone arm of Figure 1.

Figures 3 and 4 are cross-sections taken at lines III—III and IV—IV, respectively, of the phonograph tone arm of Figure 1.

I claim:

The ornamental design for a phonograph tone arm or the like, as shown.

JOSEPH B. FEDERICO.
